UNITED STATES PATENT OFFICE.

ROLAND D. GOULD, OF HOOD RIVER, OREGON, ASSIGNOR OF ONE-HALF TO FLORENCE P. GOULD AND ONE-HALF TO DE FOREST GOULD, OF HOOD RIVER, OREGON.

ENVELOP HOLDING AND FEEDING ATTACHMENT FOR TYPE-WRITERS.

1,121,088.

Specification of Letters Patent.

Patented Dec. 15, 1914.

Application filed November 18, 1913. Serial No. 801,676.

To all whom it may concern:

Be it known that I, ROLAND D. GOULD, citizen of the United States, residing at Hood River, in the county of Hood River and State of Oregon, have invented certain new and useful Improvements in Envelop Holding and Feeding Attachments for Type-Writers, of which the following is a specification.

10 My invention relates to typewriter attachments, and particularly to an envelop holder or basket for typewriting machines.

The primary object of my invention is to provide an attachment adapted to contain 15 a quantity of envelopes and adapted to be mounted on a typewriter machine and so constructed that when actuated the machine will feed an envelop into place on the platen of a typewriter.

20 A further object of the invention is the provision of a basket provided with means whereby a quantity of envelopes in the holder will be constantly fed or urged toward the feeding end of the holder.

25 A further object of the invention is the provision of a basket so formed that it may be adapted for use for envelopes of different sizes.

30 A still further object of the invention is the provision of a holder of the character described so formed that it may be readily attached to or detached from the paper table of a typewriting machine.

35 A further object of the invention is the provision of means whereby the feeding rollers which urge the envelopes toward the feeding end of the basket or holder may be easily removed or replaced.

40 A further object of the invention is the provision of supporting means adapted to be engaged with the upper surface of the paper table of a typewriter, such means being so formed as not to injure the finish of the machine.

45 Other objects will appear in the course of the following description.

My invention is illustrated in the accompanying drawings, wherein:—

0 Figure 1 is a side elevation of my improved envelop holder shown in connection with a typewriting machine. Fig. 2 is a longitudinal sectional view of the improved holder. Fig. 3 is a cross section on the line 3—3 of Fig. 2. Fig. 4 is a perspective view

broken away to show certain details of construction. 55

Corresponding and like parts are referred to in the following description and indicated in all the views of the accompanying drawings by the same reference characters. 60

Referring to these figures, it will be seen that my improved attachment comprises a holder or basket, as it may be termed, rectangular in form and constructed of a front plate 2, a rear plate 3, and a plurality of 65 longitudinally extending side bars 4, which are spaced upon each other. Preferably there are two of these side bars, superposed with relation to each other at each end of the basket. Each side bar is longitudinally 70 grooved upon its inner face, and preferably the side bars 4 are formed of sheet metal, the upper and lower margins of which are inwardly turned as at 5, so as to leave an inwardly extending slot 6. One of the inwardly turned margins, as for instance the margin 5^a is shorter than the opposite margin 5, for a purpose to be later stated. The bottom of the basket, or holder, is preferably formed of longitudinally extending bars 7, 80 which bars are attached to the rear plate 3, but are not attached to the forward plate 2, and these bars 7 are preferably formed, as illustrated in Fig. 3, with inwardly turned margins 8, clamping between them a rubber 85 cushioning strip 9.

The front plate 2 is formed with a barrel 10, this barrel being longitudinally slotted upon diametrically opposite faces as at 11. Within the barrel is disposed a coil compressed spring 12 which bears at its lower end against a plug 13 which fits the lower end of the barrel 10 and constitutes the means whereby the spring may be inserted or removed. The upper end of the barrel 95 is closed at 14 and disposed within the barrel and resting upon the spring is a slide 15, which preferably has the shape of the barrel and is of sufficient length as to be capable of moving steadily within the barrel. At- 100 tached to or formed with the slide 15 and projecting out through the front slot 11 is a push button or finger-piece 16. The slide 15 is formed with a neck 17 which projects out through the slot formed in the rear wall 105 of the barrel 10, and attached to the slide in any suitable manner and extending transversely of the holder and bearing against

2
the inner face of the plate 2 is a feed bar 18, the upper and lower edges of which are beveled. By bearing downward upon the push button 16 this feed bar 18 may be caused to be moved downward against the force of the spring 12, but when the push button is released the bar will be carried upward to the upper end of the barrel.

Extending transversely across the basket or holder is an upper roller 19 and a lower roller 20. The ends of these rollers are angularly cut away as at 21 so as to leave heads 22. These heads engage behind the margins 5 and 5^a of the bars 4 and roll upon the margins 5 of these bars as upon a track. The slot 6 is of such width as to permit the rollers 19 and 20 to roll freely downward toward the front end of the device. The side bars 4 and the bottom bar 7 are inclined upward and rearward, as illustrated in Fig. 1 and thus gravity will cause the rollers 19 and 20 to roll toward the front of the machine. These rollers 19 and 20 constitute feed rollers or followers bearing against the envelop disposed within the basket or holder and urging them toward the front plate 2 and into position to be engaged by the feed bar 18.

The front plate and the rear plate are both formed with openings 23 adapted to receive guide bars 24. These guide bars are for the purpose of forming guides between which relatively short envelops may be placed and guided. Preferably the side bars 4 are spaced from each other a distance to receive between them envelops of commercial size, that is, 9 $\frac{1}{2}$ inches long by 4 inches wide, and the holes 23 are so disposed that the rods 24 when put in position will be spaced apart a distance sufficient for holding small sized envelops such as envelops 6 $\frac{1}{2}$ x 3 $\frac{1}{2}$. It will of course be understood that the holder may be made of any desired size adapted to hold any particular style of envelop. These rods 24 are removable from the perforations 23 and when removed may be contained within a casing 25 formed by turning over the upper end of the plate 3. This casing is closed at one end and the other end has a lid or door 26 adapted to be turned down in position to close the casing or turned up to permit the withdrawal of the rods 24.

While I do not wish to limit myself to this special means for supporting the holder upon a typewriter, I have shown for this purpose the holder as formed with oppositely disposed bolts 27. Each of these bolts is formed with a handle 28 weighted at its outer end. These bolts are each mounted within a tubular barrel 29, this barrel being preferably formed with a bayonet slot 30 and each bolt being provided with a pin 31 operating within this slot. The bolts are spaced from the plane of the lower faces of

the bars 7 sufficiently to permit the bars 7 to rest upon the upper face of the paper table 32 of the typewriter and with the bolts engaging beneath the paper table. The holder is so formed that when the bolts are engaged beneath the upper end of the paper table, the discharge opening 33 of the holder will come in line with the space behind the platen 34 of the typewriter and in front of the guide roller 35, if one is used.

It is to be noted that the weighted arm 28 tends to hold the pin 31 in the angular path of the bayonet slot 30 and hold the bolt in its projected position. It is only by lifting the arm 28 that the pin 31 may be disengaged from the slot and the bolt retracted. Thus the bolts are normally held locked in position beneath the paper table.

For the purpose of providing means for adjustably regulating the width of the opening 33 so that the device may be adapted for feeding envelops of various thicknesses, I provide the members 36, shown in Fig. 2, which fit in the slots formed by the overturned members 8 at the forward ends of the bars 7. These members 36 are simply inserted in the lower ends of the bars 7 and may be shifted nearer to or farther from the forward wall 2 of the holder. As the extremities of the members 36 are downwardly and rearwardly turned they provide rounded surfaces over which the envelops may readily pass and will not impede the downward passage of the envelop. In order to cushion the shock and jar incident to the downward movement of the slide 15 and the slide 15 with the upper end of the slide casing 10 I mount upon the plug 13 the pin 37 which at its upper end is formed with a socket to receive a cushioning plug 38. It will be seen that inasmuch as this pin 37 is mounted upon the plug 13, the downward limit of movement of the slide 15 may be readily adjusted by adjusting the plug 13. The upper end of the slide 15 is formed with a cushion 39 of rubber or like cushioning material so as to deaden the impact of the slide 15 with the upper end of the casing 11 when the slide 15 moves upward under the action of the spring 12.

The operation of my invention is as follows: The envelops are placed upside down in the holder with the flaps disposed in front and extending upward. The upper rollers or feed rollers 19 will gravitate toward the lowest portion of the holder and thus urge the envelops toward the front of the machine. Now when it is desired to address an envelop the push button 16 is depressed, which carries down with it the bar 18, causing the envelops to be fed downward through the opening 33 into the space between the members 34 and 35. As soon as pressure upon the push button 16 is released, the spring will cause the slide 15 to

- move upward to a position where the feed bar 18 may again engage with the succeeding envelop. As the envelops are discharged from the holder the rollers 19 and 20 will 5 feed the envelops forward. If it is desired to use a smaller sized envelop the guide rods 24 are disposed in the perforations 23, as before explained. It will be noted that this holder is quickly attachable or detachable 10 from any ordinary machine and inasmuch as the bolts 27 only engage beneath the shield 32 of the holder may be shifted into such position as to bring the envelop accurately over the point of intersection of 15 the rollers 34 and 35. It will be noted that the bars 4 not only act as guide bars for the rollers 19, but that they also form the sides of the holder or basket. Inasmuch as the bottom of the basket is formed by the bars 20 7, and these bars carry cushions upon their under faces, it is obvious that the holder will not scratch or mar the surface of the shield upon which the holder is mounted. It will be seen that the operation of feed- 25 ing envelops to the platen is very simple and that the envelops, if desired, may be fed in rapid succession.
- Having thus described the invention what is claimed as new is:—
- 30 1. A typewriter attachment comprising an envelop holder, longitudinal downwardly inclined members on the envelop holder forming the sides thereof and forming tracks, feed rollers or followers mounted upon the said tracks and gravitating toward the lower ends of the tracks, and means at the forward end of the holder for feeding envelops downward through the bottom of the holder.
- 40 2. An attachment for typewriters comprising an envelop holder adapted to be disposed upon the typewriter above the platen thereof and including a front wall, downwardly inclined bottom bars and downwardly and forwardly inclined side bars, gravity-actuated followers mounted upon the side bars of the holder and means for feeding envelops downward through the bottom of the holder.
- 50 3. An attachment for typewriters comprising an envelop holder adapted to be disposed upon a typewriter above the platen thereof and including a front wall, a rear wall, a downwardly and forwardly inclined side bars, the margins of the side bars being over turned upon the inside face thereof to form tracks, the bottom of the holder being formed with a transversely ex- 55 tending feed slot at its forward end, gravity actuated follower rollers mounted in said tracks, and means for feeding envelops through said slot.
4. An attachment for typewriters comprising an envelop holder adapted to be dis-
- posed upon a typewriter above the platen thereof and having a feed opening in its bottom at its forward end, the front wall of the holder being slotted, a slotted barrel mounted on the front wall, a spring disposed 70 in the barrel, a slide disposed in the barrel, a feed bar disposed on the inside of the front wall and connected to said slide, and a push button mounted on the slide and projecting through the front wall of the said 75 barrel.
5. An attachment for typewriters comprising an envelop holder having a front wall and a discharge slot co-incident with the inner face of the front wall, a barrel mounted on the front face of the front wall and having a slot opening upon the inner face of the front wall, and a diametrically opposed slot, a removable plug in the bottom of the barrel, a spring resting upon said 80 plug, a slide in the barrel engaged by the spring, a feed bar disposed upon the inner face of the front wall and connected to said slide through said slot, a button upon the outer face of the barrel connected to said 85 slide through the second-named slot, and means for detachably clamping the holder upon the typewriter.
6. An attachment for typewriters comprising an envelop holder adapted to be disposed upon a typewriter above the platen thereof and to rest upon the paper table of the typewriter, said holder having a bottom formed of longitudinally extending strips having inwardly bent margins, cushions 90 mounted upon the bottom of the strips and held in place by said margins, means for feeding envelops toward the forward end of the holder, and means for discharging envelops one by one through a feed opening 95 in the bottom of the holder.
7. An envelop holder for typewriters having a front wall, a rear wall and spaced sides, and a bottom, the bottom being formed with a feed opening adjacent the forward 100 wall of the holder, means for urging envelops along the holder toward the feed opening, and auxiliary guide bars adapted to be disposed longitudinally in said holder parallel to the permanent sides to guide envelops along the holder shorter in length 110 than the distance between said side bars.
8. An attachment for typewriters comprising an envelop holder adapted to be disposed on the typewriter above the platen 115 thereof, said holder having a bottom formed of longitudinally extending strips having downwardly and inwardly bent margins, said strips extending from the rear wall nearly to the front wall of the holder, and 120 members having downwardly curved terminal ends received between the margins of the strips and adjustable toward and from the front wall to thereby regulate the size of 125 the feed opening.

9. An attachment for typewriters comprising an envelop holder adapted to be disposed on the typewriter above the platen thereof and having front and rear walls, 5 and a bottom having a feed opening co-incident with the front wall, a vertical barrel disposed in the front wall, a slide in the barrel, a spring in the barrel urging said slide upward, a feed bar operating on the 10 inside face of the front wall and operatively connected to said slide, a push button on the outer face of the barrel and connected to the

slide, a cushioning member disposed in the lower end of the barrel and receiving the impact of the slide on its downward movement, and means for cushioning the impact of the slide against the upper end of the barrel.

15

In testimony whereof I affix my signature in presence of two witnesses.
